UNITED STATES PATENT OFFICE

166,865

CORN BUTTERING IMPLEMENT

James Mesi, Chicago, Ill.

Application January 29, 1952, Serial No. 18,283

Term of patent 14 years

(Cl. D44—5)

To all whom it may concern:

Be it known that I, James Mesi, a citizen of the United States, residing at Chicago, in the county of Cook and State of Illinois, have invented a new, original, and ornamental Design for a Corn Buttering Implement, for which the following is a specification, reference being had to the accompanying drawing, forming a part thereof, in which:

Fig. 1 is a top plan view of a corn buttering implement showing by new design;

Fig. 2 is a bottom plan view;

Fig. 3 is a front elevational view, the rear elevational aspect being the same;

Fig. 4 is a side elevational view thereof, the opposite side aspect being the same; and

Fig. 5 shows a partial cross section taken on the line 5—5 of Fig. 3.

I claim:

The ornamental design for a corn buttering implement, substantially as shown.

JAMES MESI.
